UNITED STATES PATENT OFFICE.

DAVID PERRET, OF NEUFCHÂTEL, SWITZERLAND.

STEM-WINDING WATCH.

SPECIFICATION forming part of Letters Patent No. 378,974, dated March 6, 1888.

Application filed July 1, 1887. Serial No. 243,082. (No model.) Patented in France May 28, 1887, No. 183,837.

To all whom it may concern:

Be it known that I, DAVID PERRET, residing at Neufchâtel, in Switzerland, have invented a new and useful Improvement in Watches, 5 (a patent having been granted to me in France May 28, 1887, No. 183,837,) of which the following is a specification.

My invention consists of a winding-up mechanism, which is intended to be combined either 10 with watches provided with the system of hand-setting described in my patent, No. 293,779, dated the 19th day of February, 1884, or with a similar hand-setting mechanism not actuated by the stem.

15 In the accompanying drawings, Figure 1 is a top view of the movement after withdrawing the plate P, which is separately shown in Fig. 2, and which is intended to cover the wheels shown in Fig. 1. Q and R are the hand-setting wheels disposed as in Patent No. 293,779, and actuated by means of a knob, as shown in said patent. Fig. 3 is a vertical section through the winding-up mechanism. Fig. 4 shows separately the crown and stem; Fig. 5, a section of the stem-pinion; and Fig. 6 an elevation of the crescent-plate of the regulator.

In all the figures similar letters refer to similar pieces.

Upon the stem A there is affixed a crown, 30 S, and a disk, B, forming a groove, in which passes a screw, C, eccentrically screwed through the pendant D. The pivot a of A turns in a corresponding hole of the pillar N, which is affixed to plate O. Said pillar N carries a screw, M, the head of which forms a pivot for the double wheel G H. The plate P prevents the wheels G, H, I, Q, and R rising off their pivots. The wheel I is affixed to a squared portion of the mainspring-axis, and is normally 35 in gear with H.

The wheel G is screwed to H, and has a range of click-teeth on its periphery corresponding to the teeth of the pinion E, which slides upon the stem A, and which is pressed against the 40 wheel G by means of a spring, F.

The stem-pinion of other stem-winding mechanism is usually made of two parts, forming a sort of clutch or coupling-box; but my stem-pinion E is formed of only one part, having only one range of teeth, which plays indifferently as a clutch when the stem is turned from right to left, or as a driving-pinion when the stem is turned from left to right.

The stem A is formed of rolled square steel and affixed to the crown S. The steel pinion 55 E is provided with a round hole, into which is inserted a brass tube, e, with squared hole.

The regulator K is provided with a vertical projection, K', which passes through the opening k of plate P, and to which is affixed a little 60 crescent, L', provided with a projection forming a hand for indicating the position of the regulator and covering the opening k, so as to have no dust entering said opening. L is a ring which is affixed by screws to the plate P 65 to hold in place the glass O, which allows the escapement to be examined without removing the plate P.

Having thus described my invention, what I claim is—

1. A winding-up mechanism for watches, composed of a stem, A, of square metal, affixed to the crown S, and a disk, B, and a pivot, a, combined with a screw, c, passing eccentrically through the pendant D, a spring, F, sliding 75 pinion E, pillar N, screw M, and double wheel G H, substantially as shown and described, and for the purpose specified.

2. The combination, with the gears H M and stem-winding mechanism, of the plate P, that 80 retains such gears in place, and is provided with an opening, and the movable crescent L', that is connected with the regulator, substantially as specified.

Signed by me this 10th day of June, 1887.

DAVID PERRET.

Testimony:
